CURLER

Arne Bybjerg Pedersen, 42-46 Skibbrogade,
Kalundborg, Denmark

Filed Jan. 3, 1966, Ser. No. 405

Term of patent 14 years

(Cl. D86—10)

FIGURE 1 is a side elevational view of a curler showing my new design,

FIGURE 2 is a sectional view taken on the line 2-2 of FIGURE 1,

FIGURE 3 is a sectional view taken on 3-3 of FIGURE 2,

FIGURE 4 is a sectional view taken on 4-4 of FIGURE 2,

FIGURE 5 is a sectional view taken on 5-5 of FIGURE 2,

FIGURE 6 is a sectional view taken on 6-6 of FIGURE 2, and

FIGURE 7 is an end elevation view taken from the right of FIGURE 1.

The dominant features of my design consist of the arrangement and shape of the pins on the curler body. More particularly, as shown in FIGS. 3-5, the pins alternate in height in their rows and vary in shape along the

circumference, and as shown in FIG. 6 each row is separated from its adjacent row by a row of low rounded pins of uniform height so as to present a uniform appearance as shown in FIG. 1.

I claim:

The ornamental design for curler, as shown and described.
